P. M. RAINY

SELECTING SYSTEM

Filed Aug. 17, 1920

UNITED STATES PATENT OFFICE.

PAUL M. RAINY, OF GLEN RIDGE, NEW JERSEY, ASSIGNOR TO WESTERN ELECTRIC COMPANY, INCORPORATED, OF NEW YORK, N. Y., A CORPORATION OF NEW YORK.

SELECTING SYSTEM.

Application filed August 17, 1920. Serial No. 404,212.

To all whom it may concern:

Be it known that I, PAUL M. RAINY, a citizen of the United States, residing at Glen Ridge, in the county of Essex, State of New Jersey, have invented certain new and useful Improvements in Selecting Systems, of which the following is a full, clear, concise, and exact description.

This invention relates to selecting systems and particularly to new and useful improvements in printing telegraph systems of the start-stop type.

An object of the invention is the provision of a printing telegraph system of the above character arranged for either simplex or two way operation and one which does not require two way balancing equipment for two-way operation.

Another object of the invention is the provision of means associated with the transmitting and receiving equipment at each of a plurality of stations whereby these equipments may be alternately connected with the telegraph circuit connecting such stations.

This invention is particularly suitable for handling telegraphic traffic between stations where the direction of main traffic varies during the day or during a given period of time. There are many instances where during the morning the main traffic is in one direction, that is, from one city to another, while during mid-day the traffic is evenly distributed in both directions, and during the afternoon or evening hours the main traffic is in the direction opposite to that of the morning traffic.

The system of this invention is so arranged that it may be operated simplex during the morning and evening hours or when the main traffic is in one direction, and may be operated in both directions when the traffic is more evenly distributed in both directions.

The system possesses the advantage that it may be readily changed from two way to simplex operation or vice versa, and approximately the same number of words per minute can be handled in either direction by simplex operation as can be handled in both directions by two way operation. This, as will be evident from the following description, is ac-

complished in an efficient and reliable manner without the provision of expensive apparatus.

It is to be understood that the term "two way operation" as herein used, does not mean the simultaneous transmission of signaling impulses in both directions, but instead means the alternate transmission of message characters from each end of the signaling conductor.

For attaining the above objects, the invention contemplates the employment of a transmitting and receiving distributor of the start-stop type at each station on a telegraph circuit, which serve to connect the equipments individual thereto with the telegraph circuit. In order that the stations at which such equipment is located may alternately transmit and receive message impulses over such circuit, means is provided under the control of the distributors for accomplishing this result; that is, the transmitting distributor, just after clearing out the impulses stored in the signal-storing means, causes the operation of further means for connecting the receiving distributor with the telegraph circuit for the reception of a group of character impulses from the distant station, where the transmitting distributor is automatically connected with the line after the receipt of such impulses.

A better understanding of the invention may be had from the following detailed description when considered in conjunction with the accompanying drawing, wherein only so much of the system has been shown as is necessary for a clear understanding of the invention.

Referring now to the drawing wherein there is shown a line 5 extending to a distant station where apparatus similar to that shown in the drawing is located, it will be seen that connected to the line 5 is a transmitting distributor 7 and a receiving distributor 6. The former distributor connects the transmitting apparatus to the line, while the latter connects the receiving recording mechanism thereto.

The transmitting apparatus comprises current control means 8, which in the pre-

ferred form of the invention is a tape transmitter, though obviously a keyboard transmitter may be substituted in its place. The transmitter 8 embodies a series of contacts 9, 10, 11, 12 and 13 which are arranged to be selectively actuated by selectively operated members controlled by perforations in the transmitting tape (not shown). In order that the transmitting tape may be 5 advanced to bring the next succeeding group of perforations in alignment with the contacts 9 to 13, inclusive, a magnet 14 is arranged to be operated upon each revolution of the brush arm of the transmitting 10 distributor 7 for accomplishing this result, as will be more clearly described herein-after. Associated with the contacts 9 to 15, inclusive, there is a plurality of signal storing relays 15, 16, 17, 18 and 19 which 20 are provided for storing the impulses in accordance with the operation of the selected contacts. Each of these relays has two windings, one of which serves to initially energize the relay, while the other 25 serves to maintain the relay energized after its contacts have once been closed. Each relay is also provided with two armatures, one for extending circuits to the segments of the transmitting distributor 7; and the 30 other serving to complete a locking circuit therefor.

The recording mechanism shown at 20 embodies a series of selecting magnets 21, 35 22, 23, 24 and 25 which have their windings connected with the various segments of the segmented ring of the receiving distributor 6. Thus the windings of these magnets will be successively connected, upon the release 40 of the brush arm 63 with the front contact of relay 48 which is energized in accordance with the impulses received from the distant station over the line conductor 5. The conductor 26 which is shown extending from 45 a segment of the receiving distributor may be connected with a printing magnet for effecting the printing of a character as determined by the operation of the selecting magnets.

50 The transmitting distributor comprises a brush arm 27 which is frictionally mounted on a constantly revolving shaft 28. The arm 27, is held against rotation by means of a latch 29 under the control of a release magnet 30. Secured to this brush arm 27 is a pair of brushes 31 and 32. The former of these brushes connects the continuous ring 33 with the segments 34, 35, 36, 37 and 38, to which the upper armatures of 55 the storing relays are connected. The latter brush, however, bridges the continuous ring 40 with the local segments 41, 42 and 43.

In order that the storing relays will not 60 be operated for storing the impulses until the distributor arm 27 has completed its

cycle, a relay 54 is provided, which is adapted to be energized upon the energization of any one of the storing relays 15 to 19, inclusive. The energization of this relay 54 opens at its contacts the initial energizing circuits of the storing relays, which are completed through the selecting contacts of the tape transmitter. Upon the passage of brush 32 over segment 43, a circuit is completed including the relays 47 and 61 with 70 the source of battery. Relay 47 in operating opens at its contact the energizing circuit of relay 54 as well as the locking circuit of the storing relays. Thus it is seen that after this relay is operated and released, the storing relays 15 to 19 inclusive 75 may then be actuated for storing impulses in accordance with the actuation of the selected contacts.

The reception of impulses is accomplished 80 by providing a line relay 48 which is connected in circuit with the conductors 4 and 5, and the alternate contacts of key 52 the latter of which, as previously described, extends to a distant station. This relay 48 85 is normally energized by current flowing from the battery 77, conductor 4, through the contact 70 of switching key 52, back contact of relay 53, contact 78 of key 52 and winding of relay 48 to the line 5. The front 90 and back contacts of this relay 48 are connected with segments 51 and 50 respectively, of the receiving distributor 6. These segments 50 and 51 are arranged to be bridged 95 with the segments associated therewith by means of a brush 60. From this it is seen that the energization of release magnet 58 for releasing the arm 63 is controlled 100 through the back contact of relay 48, while the energization of the selecting magnets is controlled through the front contact 105 thereof. Thus if the front contact of this relay is closed at the time brush 60 is passing over segment 71, selecting magnet 21 110 will be energized for effecting the operation of the selecting mechanism controlled thereby. This circuit extends from grounded battery, winding of selecting magnet 21, 115 segment 71, brush 60, segment 51, front contact of relay 48, and normal contacts and armatures of relays 57 and 61 to ground.

A brief description of the apparatus employed having been given, it is thought that the invention may be more readily understood from a description of the operation of the system. Since the simplex operation of the system differs but little from the system illustrated in Patent No. 1,324,838, December 16, 1919, a description thereof 120 is considered unnecessary. The following 125 description will therefore be devoted to the operation of the system wherein the transmitting and receiving equipments are alternately connected with the line conductor or telegraph circuit.

In the preferred form of the invention, a five unit code consisting of impulses of current and intervals of no current is employed in the selection of each character. 5 Therefore, in describing the operation of the system, let it be assumed that a signal composed of the following units is to be transmitted: current, no current, no current, current and current. When it is desired to 10 operate the system in the above manner, key 52 must be actuated to close its alternate contacts. The actuation of key 52 and the closure of the alternate contacts thereof such as 68, 70, 74 and 78 places the energizing circuit of relay 48 under the control of relay 53 rather than being directly controlled 15 through the segments of the transmitting distributor, as in the case when the key 52 is in its normal position. After the alternate contacts of key 52 have been closed, in order to condition the system for operation, it is necessary to momentarily operate a start key for causing the closure of contact 56. With the alternate contacts of key 52 20 closed, the closure of contact 56 causes the energization of relays 57 and 64, the energizing circuits of which may be traced over battery, through the right-hand winding of each of these relays, upper alternate contact 25 of key 52 and contact 56 to ground. Upon the closure of the left-hand contact of each of these relays, a locking circuit is established, one of which is under the control of relay 61, while the other is controlled 30 through the segments of the transmitting distributor 7. The closure of the right-hand contact of relay 57 establishes an energizing circuit for relay 53 which upon opening its normal contacts disconnects the battery 35 77 from the winding of relay 48. Relay 48 thereupon releases its armature and closes its back contact. Release magnet 58 will, however, not be energized at this time as the 40 energizing circuit therefor was previously broken due to the energization of relay 57 upon the closure of contact 56. Relay 64 in closing its right-hand contact establishes an energizing circuit for release magnet 30 which is thereupon operated. The operation 45 of this magnet and withdrawal of latch 29 permits the arm 27 to revolve with the constantly revolving shaft 28.

In accordance with the previously mentioned group of selecting units or impulses, contacts 9, 12 and 13, of the transmitter will be closed, thereby completing the energizing circuit for restoring relays 15, 18 and 19. These circuits extend from grounded battery, through the windings of these relays, the closed contacts of the transmitter 8 and the normal contact of relay 54 to ground. Storing relays 15, 18 and 19 thereupon close their contacts to extend the circuits controlled by the upper armatures of these relays to the segments of the transmitting dis- tributor which are subsequently connected with the line 5 by the brush 31, and also establish locking circuits upon the closure of the lower contact of each of these relays. Relay 54 is also energized at this time and 50 attracts its armature for opening the initial energizing circuit of the storing relays 15, 18 and 19. The operation of release magnet 30, as before described, withdraws the latch 29 and permits the brush arm 27 to revolve 55 with the shaft 28. The release of the arm 27 causes the circuit extending from the battery 77 to the line 5, through the segment 39, the brush 31 and ring 33 of the transmitting distributor to be broken. This therefore disconnects the battery 77 from the line and permits relay 48 at the distant station to close its back contact. The closure of the back contact of relay 48 of the distant station completes the energizing circuit for release magnet 58. This circuit may be traced from the battery through the winding of release magnet 58, segment 59, brush 60, segment 50, back contact of relay 48, normal 60 contact of relay 57 and the contact and armature of relay 61 to ground. Release magnet 58, in operating, withdraws the latch 62 for permitting the arm 63 to revolve. 65 The passage of the sending brush 32 over segment 42 completes an energizing circuit for magnet 14. This magnet, in operating, causes the operation of suitable mechanism (not shown) to advance the transmitting tape for positioning the next succeeding group of perforations in alignment with the selecting contacts 9 to 13 inclusive, but inasmuch as relay 54 at this time is energized, the storing relays connected with the actuated contacts will not be energized. Brush 32 in passing off of segment 41 opens the 70 locking circuit of relay 64 which is thereupon deenergized, and disconnects the source of battery from the winding of release magnet 30. Thus the latch 29 will be restored to its normal position for engaging the arm 27 after it has completed one cycle. As the arm 27 revolves, segment 34 to which the upper armature of relay 15 is connected is bridged with ring 33 by the brush 31 and since storing relay 15 is energized, the battery 77 will be connected with the line conductor 5. This circuit may be traced from battery 77 through conductor 4, contact 70 of key 52, contact 69 of relay 53, contact 68 of key 52, conductor 67, upper armature of relay 15, conductor 66, segment 34, brush 31, segment 33, conductor 65, contact 74, conductor 63 and contact 75 of relay 53 to the line conductor 5. At the distant station, relay 48 is thus energized for completing the circuit for the selecting magnet 21 upon the passage of brush 60 over segment 71. Selecting magnet 21 will thereupon be energized over a circuit extending from battery, through the winding of selecting magnet 21, 120 125 130

segment 71, brush 60, segment 51, contact of relay 48, normal contact and armature of relay 57 and the contact and armature of relay 61 to ground, for operating the selecting mechanism controlled thereby. Since selecting relays 16 and 17 have not been energized, no impulses will be transmitted to the line upon the passage of the brush 31 over the segments to which the upper armatures 10 of these relays are connected. Relay 48 at the distant station will thus remain deenergized during the period brush 31 is passing over segments 35 and 36, and selecting magnets 22 and 23 at the distant station will also 15 not be operated for operating the selecting mechanism controlled thereby. However, when the brush 31 passes over segment 37, an impulse will be transmitted to cause the operation of relay 48 in the manner previously described. The same is true when the brush 31 passes over segment 38. The selecting magnets at the distant station corresponding with the storing relays will of course be operated in the same manner as 20 previously described for relay 21.

Just before the arm 27 is arrested by the latch 29, segment 43 is bridged with ring 40 by the brush 32. Relays 47 and 61 are thereupon energized over a circuit extending 25 from battery, through the winding of relay 61, segment 43, brush 32, and ring 40 to ground. Relay 47 functions as previously described while relay 61, upon opening its contact, causes the deenergization of relay 35 57. This relay 57, in releasing its armature, removes battery from the winding of relay 53, which closes its normal contacts. The closure of the normal contacts of relay 53 again connects the battery 77 with the winding of relay 48 which thereupon attracts 40 its armature for preventing the energization of release magnet 58 upon the closure of the contact of relay 61.

When the brush arm 63 of the receiving 45 distributor at the distant station, has nearly completed its cycle, brush 60 carried thereby bridges segments 72 and 73, thus causing the operation of the printer magnet connected with the conductor 26 and the completion 50 of a circuit including start relay 64 and relay 57. This latter circuit may be traced from battery, through the right-hand windings of each of these relays, contact 74 of key 52, contacts 76, segment 73, brush 60 55 and segment 72 to ground. Relay 57, in operating, completes through its right-hand contact an energizing circuit for relay 53. This relay 53, in opening its normal contacts, disconnects the line relay 48 from the 60 line circuit, while in closing its alternate contacts extends the conductors 4 and 5 to the transmitting distributor, through the alternate contacts of key 52. As previously described in connection with the initial starting 65 of the system, release magnet 30 at the

distant station is energized upon the closure of the right-hand contact of relay 64. The latch 29 is thereupon withdrawn from engagement with the arm 27 which is allowed to revolve with the shaft 28. If any of the 70 storing relays 15 to 19, inclusive, have been energized, the impulses stored due to the operation of these relays will be transmitted over the conductor 5 in the manner above described. 75

After the transmission of the message has been completed, and it is desired to stop the distributors, key 76 is opened during one receiving cycle. The sixth impulse is thus interrupted and does not reach the starting 80 relay 64; hence the distributors at both stations are stopped.

From the foregoing description it will be seen that the system of this invention is one which may be readily changed from simplex operation to two way operation without the employment of duplex balancing equipment. When it is desired to transmit messages in one direction only, the key 52 is positioned, as shown in the drawing, and 90 when it is desired to transmit message characters alternately from each end of the line circuit, the key 52 is actuated to close its alternate contacts in order that the transmitting and receiving distributors at both 95 stations may co-act properly in the simultaneous transmission and reception of the message characters. It is to be understood that transmission of messages in both directions simultaneously does not mean the simultaneous transmission of impulses in both directions. The groups of impulses representing the characters of a message are transmitted 100 alternately from each end of the line conductor. 105

What is claimed is:

1. A printing telegraph system comprising a line and a plurality of stations connected by said line, periodically rotating transmitting and receiving distributors at each of said stations, a relay normally connected in said line for controlling the operation of said receiving distributor, a relay adapted to be energized by said receiving distributor and thereafter controlled by said transmitting distributor, and a further relay responsive to the operation of said second-mentioned relay for disconnecting said first mentioned relay from the line and connecting said transmitting distributor thereto. 110 115 120

2. A printing telegraph system comprising a line, a plurality of stations connected by said line, periodically rotating transmitting and receiving distributors at each of said stations, circuits controlled by each of said distributors, a relay normally connected in said line for controlling the operation of said receiving distributor, a relay controlled initially by said receiving distributor and thereafter by said transmitting distributor, 130 125

a further relay responsive to the operation and reconnection of the line relay in the line of said second mentioned relay for disconnecting said first mentioned relay from the line and connecting thereto said transmitting distributor, and means operative by said 5 transmitting distributor for causing the de-energization of said second mentioned relay

In witness whereof, I hereunto subscribe 10 my name this 12th day of August A. D., 1920.

PAUL M. RAINES.
